UNITED STATES PATENT OFFICE.

JOHN F. NEWSOM, OF PALO ALTO, CALIFORNIA.

TIME-CONTROLLED ELECTRIC SWITCH.

Application filed September 28, 1921. Serial No. 503,872.

To all whom it may concern:

Be it known that I, JOHN F. NEWSOM, a citizen of the United States, and a resident of Palo Alto, Santa Clara County, State of California, have invented a certain new and useful Time-Controlled Electric Switch, of which the following is a specification.

The invention relates to a time controlled electric switch which is actuated at variable 10 predetermined intervals to open an electric circuit.

An object of the invention is to provide an apparatus which operates at predetermined time intervals to move a switch opening 15 element, which element acts to open the switch in the event that it is closed.

Another object of the invention is to provide a switch opening mechanism which is operable at predetermined variable time 20 periods to open the switch at such time periods in the event that it is closed.

A large number of persons indulge in the habit of reading in bed, usually for the purpose of inducing sleep, and often fall asleep 25 with the electric reading lamp burning. The presence of the burning lamp is not conducive to restful slumber and causes a weariness and irritation of the eyes. In order to avoid this, the reader must constantly bear in mind that he must switch off the light before he falls asleep and this continual thought retards the coming of sleep and the slight physical exertion necessary to switch off the light often dispels the 30 drowsiness which was produced by reading. The device of my invention will operate to switch off the lamp at the end of a predetermined time period, which may be varied to suit the habits of the reader, so that he may retire and read, without any thought 35 of the burning lamp, since he knows that the light will be switched off at the end of a selected interval. If it is his habit to read for about ten minutes, he may set the device to open the circuit at the end of fifteen minutes and if he is in the habit of reading longer, he may set the device for a longer elapsed time period. If he is still reading when the circuit is opened, he need 40 merely press a button to again close the circuit, which will again be opened at the end of the selected time period.

The invention possesses other advantageous features, some of which, with the foregoing, will be set forth at length in the following description, where I shall outline

in full, that form of the invention which I have selected for illustration in the drawings accompanying and forming part of the present specification. In said drawings I 60 have shown one form of the apparatus of my invention but it is to be understood that I do not limit myself to such form, since the invention, as set forth in the claims, may be embodied in a plurality of forms. 65

I have referred to the utility of the invention in connection with a night reading lamp, but it is to be understood that its utility is not limited to such use, since it may be advantageously employed in many 70 other instances where it is desirable to open an electric circuit at the end of a predetermined variable time period.

Referring to said drawings:

Figure 1 is a perspective view of the apparatus of my invention enclosed in a casing, the casing being shown in section. 75

Figure 2 is a fragment of the casing.

The apparatus of my invention is arranged in connection with a suitable clock mechanism, not shown, which is provided with a release mechanism, such as the striking release mechanism employed on striking clocks. Many clocks are provided with a quarter hour striking mechanism, which is released 80 every quarter hour to strike a gong or chime and since these mechanisms are well known, they are not shown or described herein. The apparatus of my invention is connected to the striking release mechanism, 85 but the striking mechanism and gong is omitted for obvious reasons. In the present construction, I have shown an apparatus which is operative to open the circuit at the end of either a fifteen minute interval, a 90 thirty minute interval or a sixty minute interval, depending upon the setting of the apparatus. Many forms of devices may be employed for opening the circuit, and in the present construction, for the purpose 100 of illustration, I have shown an apparatus actuated by a clock mechanism provided with a strike release mechanism, which operates at the fixed predetermined intervals to cause rotation of the shaft 2, the shaft 105 being rotated preferably for a single complete revolution. Secured to the shaft is a pinion 3 which meshes with a gear 4, rotational movement of which, operates or tends to operate the switch. Secured to and 110 projecting laterally from the gear 4, are a plurality of regularly spaced pins arranged

around the periphery of the gear, the spacing of the pins being equivalent to the circumference of the pinion 3, so that one rotation of the pinion moves the gear 5 through an angle corresponding to the angular spacing of the pins. In the present construction, the pins are arranged to represent three different time intervals, namely: 15 minutes, 30 minutes and 60 10 minutes, although other time intervals may be selected when desired.

The pins are consequently formed in three different lengths, pins 5 being the shorter, pins 6 being of intermediate length and 15 pins 7 being the longer. A plane passed through the pins adjacent to the gear will cut all of the pins. A plane passed through further from the gear will cut pins 6 and 7 and a plane passed through further from 20 the gear will cut pins 7. Thus, by arranging a trip in any one of these planes the trip will be actuated at time intervals corresponding to the spacing of the pins in the selected plane. In the first plane the 25 pins have a 15 minute time spacing; in the second plane, a thirty minute time spacing and in the third plane a sixty minute time spacing. While I have described one form of timing mechanism, it is to be understood that I do not limit myself to such form, since other and well known mechanisms may be employed with equal advantage.

Disposed adjacent the gear 4 is a shaft 8 35 having a sleeve 9 thereon, the sleeve being slidable longitudinally on the shaft and being rotatable therewith. Extending from the sleeve 9 into the circular path of the pins is a trip 12 and this trip is movable 40 into the desired plane by a handle 13 extending through a slot 14 in the enclosing casing 15, the casing, at the side of the slot, being provided with characters 16 to indicate the various planes. The sleeve is thus movable 45 to bring the trip into the path of all of the pins, into the path of the pins 6 and 7, and into the path of the pins 7 only.

Projecting from the shaft 8 is a pin 17 50 which is connected to the movable arm 18 of the switch 19 arranged in circuit with the lamp 21. The shaft is rocked by engagement of the trip 12 by the adjacent pin on the gear 4, to move the arm 18 to open the circuit, which then remains open. Means 55 are provided for closing the circuit comprising a spring held button 22 extending through the casing and having a stem 23 disposed adjacent the free end of the pivoted switch arm 18. Depression of the button 60 moves the switch arm to close the circuit. When the device is to be used, the trip is set in the desired plane and the button depressed, closing the circuit, which will be 65 opened subsequently, by engagement of the trip by one of the pins 5, 6 or 7, depending

upon the setting of the trip. Other forms of setting devices may be employed without departing from the scope of this invention.

Thus, a person who reads habitually for about 30 minutes after retiring, will set the trip at the thirty minute indication, and may read and fall asleep with an untroubled mind. Should the device operate to open the circuit before sleep has come, the simple pressing of the button will restore the light and thirty minutes later it will again be extinguished.

I claim:—

1. In a time switch, a rotatable element, a plurality of projections of varying length carried by the element and extending in a direction substantially parallel to the axis of rotation of the element, a switch, and a trip for the switch in the path of the projections, said trip and member being relatively movable in an axial direction, whereby the frequency of operation of the trip may be adjusted. 80

2. In a time switch, an intermittently rotated wheel, a plurality of projections of varying lengths carried by the wheel, said projections extending in a direction parallel to the axis of the wheel, an electric switch, and a trip for the switch adopted to be operated by the projections, said trip and wheel being relatively adjustable in a direction parallel to the axis of the wheel, whereby the frequency of operation of the trip may be varied. 90

3. In a time switch, a rotatable wheel, a plurality of projections of varying length carried by the wheel, an electric switch, and a trip for the switch adapted to be operated by the projections, said trip and wheel being so relatively adjustable that it may be removed from the influence of a varying number of projections, whereby the frequency of operation of the trip may be varied. 100

4. In a time switch, a rotatable wheel, a plurality of projections of varying length carried by the wheel, an electric switch, and means for operating the switch, said means being adapted to be engaged by the projections, and being adjustable relatively to the projections whereby the frequency of operation of the switch may be varied. 110

5. In a time switch, a rotatable wheel, a plurality of pins projecting from the wheel in a direction parallel to that of the axis of rotation of the shaft, said pins being of varying lengths, an electric switch, a guide arranged parallel to the pins, and a trip for the switch adjustably mounted on the guide and arranged to be operated by a varying 120 number of the pins dependent upon its adjustment on the guide. 125

6. In a time switch, a wheel adapted to be rotated by a time mechanism, a plurality of projections of varying lengths extending from the wheel, an electric switch, a guide 130

arranged near the wheel, and a trip adjustably mounted on the guide so as to be in the path of travel of the projections and to be adjusted so as to be capable of operation by 5 a varying number of projections.

7. In a time switch, a wheel adapted to be rotated by a time mechanism, a plurality of projections of varying lengths extending from the wheel and arranged substantially 10 parallel to the axis of rotation thereof, an electric switch, and means for operating the switch in accordance with the rotation of the

wheel, comprising a guide rotatable about an axis parallel to that of the wheel, a trip member adjustably mounted on the guide so 15 that it may be successively operated, during one revolution of the wheel, by a varying number of the projections, and thereby rock the guide, and a mechanical connection between the guide and the switch. 20

In testimony whereof, I have hereunto set my hand.

JOHN F. NEWSOM.
